[57] **CLAIM**

The ornamental design for a combined bottle and cap, as shown and described.

DESCRIPTION

FIG. 1 is a top, front perspective view of a combined bottle and cap showing my new design;

FIG. 2 is a front elevation thereof, the rear elevation is the same;

FIG. 3 is a right side elevation thereof, the left side elevation is the same;

FIG. 4 is a top plan view thereof; and,

FIG. 5 is a bottom plan view thereof.

The broken lines shown in FIGS. 1 and 2 are for illustrative purposes only and do not form part of the claimed design.
